[57] ABSTRACT

A trolling attachment for an outboard motor boat. The trolling attachment is made up of two part circular disk of platelike material split in the middle and having a semicircular opening in the center for receiving the spinner of a boat motor. The two halves of the disk are hinged together at one side and a clamping attachment is provided at the opposite side for clamping the attachment to the out side diameter of the propeller hub of a boat motor. The spaced resilient segments are supported on the periphery of the opening for holding the attachment rigidly to the spinner.

TROLLING ATTACHMENT FOR A PROPELLER

REFERENCE TO PRIOR ART

The invention disclosed herein constitutes an improvement over the trolling attachment shown in U.S. Pat. No. 2,820,428.

OBJECTS OF THE INVENTION

It is an object of the invention to provide an improved trolling attachment for an outboard motor boat.

Another object of the invention is to provide a trolling attachment which is simple in construction, economical to manufacture, and simple and efficient to use.

With the above and other objects in view, the present invention consists of the combination and arrangement of parts hereinafter more fully described, illustrated in the accompanying drawing and more particularly pointed out in the appended claims, it being understood that changes may be made in the form, size, proportions, and minor details of construction without departing from the spirit or sacrificing any of the advantages of the invention.

GENERAL DESCRIPTION OF THE DRAWINGS

FIG. 1 is a side view of a boat and motor with the trolling attachment on the motor.

FIG. 2 is a rear view of the trolling attachment on a boat motor.

FIG. 3 is a side view of the attachment shown in FIG. 2.

FIG. 4 shows the attachment swung open as to remove it from the boat motor.

FIG. 5 is a cross sectional view taken on line 5—5 of FIG. 4.

DETAILED DESCRIPTION OF THE DRAWINGS

Now with more particular reference to the drawings, the trolling attachment is supported on spinner 37 of the boat motor 28. The trolling attachment is basically a disk 10 made up of two semi-circular platelike parts 11 and 12 that are hingedly connected together by hinge 13. Diametrically opposite the hinge 13, a latching attachment 14 is attached, made up of the two members 19 and 20 which are attached to the half 11 of the disk by rivets 22 which pass through the sides of the members 19 and 20 and through the platelike member 11. The fastener member 15 is made up of members 25 and 26 and attached to the plate member 12 by means of rivets 23 which pass through the inner ends of the members 25 and 26. Swivel 17 has a lateral bore which receives pivot 24. Pivot 24 passes through the swivel 17 and through the members 25 and 26 and pivotally supports the swivel member 17 between the members 25 and 26. A threaded stud 21 having a knurled head 29 is threadably received in the swivel member 17. Head 29 has a downwardly facing shoulder 27 which engages the upper surface of the members 19 and 20.

Rubber members 30 are spaced around the inner periphery of the semi-circular openings 31 and 32. Members 30 are U-shaped in cross section and are received on the disk which forms the opening which receives the spinner 37 of the outboard boat motor 28. The members 30 may be made of rubber or other suitable resilient material.

The first notch 33 is cut out of the first semi-circular disk 11 at a first side thereof and a second notch 34 is cut out of said first semi-circular disk at a position diametrically opposite the first notch 33. A first notch 35 is cut out of the second semi-circular disk 12 and a second notch 36 is cut out of the second semi-circular disk 12 at a position diametrically opposite the first notch 35. The hinge 13 is fixed to the second semi-circular disk 12 by rivets 37 and the first semi-circular disk 11 is swingably attached to the hinge 13 by a single rivet 38. The rivet 38 is supported at the center of curvature of the curved surfaces 39 defining the corner of the first semi-circular disk 11.

The spaced members 19 and 20 extend into the notch 34 and provide a space for head 29 when the device is in use. The spaced members 25 and 26 extend into the notch 36. Thus when the threaded member 21 is in clamping position shown in FIG. 2, the spaced members 14 and 15, as well as the threaded member 21, are all within the circumference of a circle defining the outer periphery of the circular disk 10. The motor 28 is shown as an outboard motor connected to the boat 40, however, instead of the outboard motor 28, an in-board-outboard motor or other suitable type of motor could be substituted for the outboard motor 28.

The foregoing specification sets forth the invention in its preferred practical forms but the structure shown is capable of modification within a range of equivalents without departing from the invention which is to be understood is broadly novel as is commensurate with the appended claims.

The embodiments of the invention in which an exclusive property or privilege is claimed are defined as follows:

1. A trolling attachment for a boat comprising a circular disk made up of two semi-circular members each having a semi-circular opening formed therein, hinge means connecting said semi-circular members together to form said circular disk, having a concentric circular opening in the center, said concentric circular opening being adapted to receive the hub of an outboard motor, resilient members spaced around the inside of said opening for frictionally engaging a spinner, and a clamping means for clamping said two semi-circular halves to said hub.
2. The attachment recited in claim 1 wherein said semi-circular members each have a first notch cut out at one side and a second notch cut out at a second side diametrically opposite said first side, said hinge means being fixed to one of said semi-circular members adjacent said first notch, said hinge means pivotally connected to the other of said semi-circular members adjacent said first notch, said first notch providing a clearance whereby one of said semi-circular members can swing about said pivot on said hinge.
3. The attachment recited in claim 2 wherein said clamping means comprises two spaced members attached to one of said semi-circular members adjacent said second notch therein, providing a space between said spaced members, and a swivel member disposed between said spaced members and pivotally attached to said spaced

65

members by a pivot passing through said spaced members,
 two second spaced members fixed to the other of said semi-circular members adjacent said second notch therein and extending from said other semi-circular member and overlying a part of said second notch therein,
 a threaded member threadably engaging said swivel

member,
 said threaded member having means being adapted to overlie said second spaced members whereby said threaded member is adapted to connect said one semi-circular member to said other semi-circular member.
